Application June 2, 1948, Serial No. 30,555

7 Claims. (Cl. 200—87)

1

The present invention relates in general to multi-contact switching devices, and more particularly to improvements in relay structures by means of which different contact positions are accomplished through successive operations of the relay. Such a relay structure finds many uses in circuit combinations wherein intermediate sequential operations are required in order to realize a desired over-all result.

An object of the invention is to provide a new and novel relay structure which embodies a simple, compact and inexpensive construction.

Another object of the invention is to provide an improved relay arrangement wherein a contact does not operate during a first energization of the relay; wherein the contact operates responsive to a following de-energization of the relay; wherein the operated contact remains undisturbed during a re-energization of the relay; and wherein the operated contact is restored to its normal position responsive to a second de-energization of the relay.

A further object of the invention is to provide a new and novel relay structure whereby a contact is operated each time the relay is energized and is restored to its normal position each time the relay is de-energized; whereby a second contact remains in its normal position during a first energization of the relay and is operated responsive to a following de-energization of the relay; and whereby the operated second contact is restored to its normal position responsive to a de-energization of the relay following a re-energization of the relay.

A feature of the invention resides in the interposing of a new and novel mechanism between the armature of the relay and a contact switch unit for controlling the operation of the contact switch unit in response to successive operations of the armature.

Another feature of the invention concerns the new and novel manner in which the mechanism interposed between the armature of the relay and a contact switch unit functions to cause the operation of the contact switch unit only when a first restoration of the armature is accomplished, and to cause the restoration of the operated contact switch unit only when a second restoration of the armature is accomplished.

A further feature of the invention relates to a novel adjusting arrangement for regulating the operation of the mechanism interposed between the armature of the relay and a contact switch unit.

Other objects and features will become appar-

2

ent from the following description together with the accompanying drawings which show a proposed embodiment by way of example.

The invention is disclosed in two sheets of drawings comprising Figs. 1 to 13, inclusive.

Fig. 1 is a top, or plan, view of the relay showing particularly the arrangement of the two operating arms of the armature and the associated contact springs comprising right and left switch units.

Fig. 2 is a right-hand side view, in elevation, of the relay showing another view of the right-hand switch unit of Fig. 1 and the parts of a lever mechanism for operating this switch unit which are not obscured by the cover plate located on the right-hand side of the relay.

Fig. 3 is a left-hand side view, in elevation, of the relay showing another view of the left-hand switch unit of Fig. 1 and the armature arm for operating same.

Fig. 4 is an end view, in elevation, of the relay showing further details of the armature and the two switch units.

Fig. 5 is a fragmentary right-hand side view of the relay, similar to the lower part of Fig. 2 with the cover plate removed. Fig. 5 shows details of the bracket attached to the relay heel piece for mounting the lever mechanism required for operating the switch unit of Fig. 2.

Fig. 6 is a left-hand side view, in elevation, of the mounting bracket shown in Fig. 5, illustrating how the mounting bracket is attached to the relay heel piece.

Fig. 7 is a fragmentary end view of the mounting bracket taken along the line 7—7 in Fig. 5.

Fig. 8 is a cross-section taken along the line 8—8 in Fig. 5, showing further details of the mounting bracket.

Fig. 9 is a right-hand side view of the relay showing the armature, the right-hand switch unit of Fig. 1 and the lever mechanism controlled by the armature for operating the right-hand switch unit, all in the normal, or non-operated, positions.

Fig. 10 is a right-hand side view of the relay showing the relationship of the armature, the lever mechanism and the right-hand switch unit after the first energization of the relay. It should be observed that the armature has moved to the operated position and that the switch unit still remains in the normal, or non-operated, position.

Fig. 11 is a right-hand side view of the relay showing how the lever mechanism automatically operates the right-hand switch unit as the arma-

ture restores to the normal position following the first de-energization of the relay. The right-hand switch unit, however, remains in the operated position and is not disturbed by the restoration of the armature.

Fig. 12 is a right-hand side view of the relay showing the relationship of the armature, the lever mechanism and the right-hand switch unit after the second energization of this relay. The armature has again moved to the operated position but the right-hand switch unit remains in the operated position of Fig. 11.

Fig. 13 shows a simple circuit arrangement for controlling the energization and de-energization of the relay winding.

Referring now more particularly to Figs. 1 to 4, inclusive, of the drawings, the electromagnetic relay therein shown comprises essentially a magnetic core 10 carrying a winding 11, a substantially L-shaped magnetic heel piece 12 secured to core 10 by means of screw 49, and a movable magnetic armature 13 pivotally mounted on the outer end of heel piece 12 and co-operating with one end of core 10. More particularly, armature 13 is pivotally secured to heel piece 12 by means of pivot pin 14, yoke 15, washer 16 and screw 17. Also, a downwardly bent tab 18 is formed integrally with washer 16 and extends through a recess (not shown) in yoke 15 into an aligned opening (not shown) in heel piece 12 in a well-known manner to prevent relative motion between yoke 15 and heel piece 12. Preferably, pivot pin 14, yoke 15 and screw 17 are formed of non-magnetic material in order to prevent these elements from interfering with the magnetic flux path between armature 13 and heel piece 12. Any of the well-known residual means can be utilized for preventing armature 13 from sticking to core 10.

Further, armature 13 carries a pair of spaced apart and inwardly directed arms 19 and 20 disposed on the opposite sides of heel piece 12 and provided with aligned holes therein which receive the opposite outer ends of pivot pin 14, the opposite outer ends of pivot pin 14 being flanged over in order to rigidly secure pivot pin 14 to arms 19 and 20 and, consequently, to armature 13. Also, arm 19 is provided with an inturned operating projection 21 (Fig. 1) which overlies the top surface of heel piece 12 and co-operates with contact switch unit 22 carried by heel piece 12. Projection 21 can be fitted with a residual (not shown) or any well-known residual means can be used for preventing projection 21 from sticking to the adjacent surface of heel piece 12 due to leakage magnetic flux therebetween. Armature 13 further carries an arm 23 and a pushing member 45 (Figs. 2 and 4) for co-operating with the lever mechanism mounted on the right-hand side of the relay (the lever mechanism is mostly concealed by cover 24 in Fig. 2 but may be observed in detail in Figs. 9 to 12, inclusive), the lever mechanism co-operating with contact switch unit 25 of the relay in the manner to be described in later paragraphs.

Switch units 22 and 25 comprise a plurality of individual flexible metallic switch, or contact, springs such as 26, 27, 28, 29 arranged in two pile-ups, each pile-up being secured to heel piece 12 by a pair of screws 30. More specifically, the base ends of the contact springs in each pile-up are spaced apart and insulated from each other by a plurality of interposed insulating pieces 31, the assembly of contact springs and insulating pieces being retained in clamped position between 75

a clamping plate 32 and heel piece 12 by the two screws 30. The contact springs need not be of the particular type or form shown in the drawings but may be of any well-known form, according to circumstance or preference. Also, the number of contact springs and the particular contact combination of each switch unit may be varied to suit any requirement.

Referring now to Figs. 5 and 6, a substantially L-shaped bracket 33 for mounting the previously mentioned lever mechanism is rigidly attached to heel piece 12 by means of screws 34 or other suitable means. Tapped bosses 35 on bracket 33 and screws 36 (Fig. 2) provide means for attaching cover 24 to retain the various levers of the lever mechanism in their respective positions. Projections 37, 38, 39 and 40 of bracket 33 provide bearing means for the various levers of the lever mechanism.

Referring now more particularly to Figs. 9, 10, 11 and 12, the lever mechanism for controlling switch unit 25 comprises four interlinked levers 41, 42, 43 and 44 controlled by armature 13 through the medium of arm 23 and adjustable pushing member 45. Preferably, levers 41, 42, 43 and 44 are formed of non-magnetic material in order to cause no irregular operation.

More specifically, lever 41 is substantially L-shaped, the left-hand half of its horizontal member being bearinged by bracket 33 and projections 37 and 38 extending therefrom, the right-hand end of the horizontal member being guided by U-shaped projection 39. Helical spring 46 seated against projection 39 and acting on shoulders 47 and 48 of the horizontal member keeps the vertical member of lever 41 firmly against pushing member 45 of armature arm 23 at all times.

Further, lever 42 is of the bell-crank type, bearinged on bracket 33 by pivot pin 50. One end of a flat spring 51 is fixedly attached to the upper arm of lever 42 in any suitable manner, the other end of spring 51 resting against lower projection 52 of lever 44. The normal tension of spring 51 causes the lower arm of lever 42 to bear down on stop stud 53 of lever 44 (Fig. 9) thereby to retain lever 44 in its lower position. Also, the lower arm of lever 42 has a shoulder 54 normally resting against projection 55 of lever 41, and the upper arm of lever 42 is notched at 56.

Further, lever 43 is also of the bell-crank type, bearinged on lever 44 by pivot pin 57. Helical spring 58 attached to the right-hand arm of lever 43 at 59 and to stud 60 of lever 44 causes the tip of the right-hand arm of lever 43 to rest on the upper arm of lever 42 just clear of notch 56 (Fig. 9) and the tip of the lower arm of lever 43 to clear projection 38 of bracket 33.

Further, lever 44 is of the sliding type and is located in the central portion bracket 33, the upper end of the lever passing over cutout 61 of bracket 33, and the central portion of the lever being bearinged by inwardly turned projections 40. The upper end of lever 44 has an inturned projection 62 (Fig. 1) which overlies the top surface of heel piece 12 for co-operating with switch unit 25. The lower end of lever 44 has an out-turned projection 52 against which projection 40 of flat spring 51 rests (Fig. 9).

Considering now the operation of the relay, Figs. 2, 3 and 9 show all movable elements of the relay in their respective normal, or non-operated, positions. When winding 11 is energized for the first time as, for example, by the closing of contact 9 (Fig. 13), armature 13 is attracted towards core 10, and projection 21 of armature arm

19 (Fig. 3) correspondingly raises bushing 63 thereby operating switch unit 22 in a conventional manner. Pushing member 45 of armature arm 23, however, does not correspondingly operate switch unit 25 because the lever mechanism mounted on the right-hand side of the relay is interposed between pushing member 45 and bushing 64 of switch unit 25 to control the operation of switch unit 25. As armature 13 moves from its normal position to the operated position of Fig. 10, pushing member 45 of armature arm 23 moves lever 41 to the right, overcoming the pressure of helical spring 46. Projection 65 of lever 41, consequently, over-rides projection 52 of lever 44 (Fig. 10) thereby locking lever 44 in its lowest position, and switch unit 25, therefore, cannot be operated at this time.

As lever 41 moves to the right, projection 55 of lever 41 presses against shoulder 54 of lever 42, thus causing the upper arm of lever 42 to move to the right until the tip of the right-hand arm of lever 43 slips into notch 56 of lever 42 (Fig. 10), helical spring 58 supplying the power for latching the right-hand tip of lever 43 into notch 56. The movement of the upper arm of lever 42 to the right increases the tension in flat spring 51 but projection 65 of lever 41 continues to retain lever 44 in its lowest position. Lever 44, therefore, cannot cause the operation of switch unit 25 at this time. Switch unit 25, consequently, is not operated upon the first energization of winding 11.

When winding 11 is de-energized for the first time, as, for example, by the opening of contact 9 (Fig. 13) armature 13 is released and returns to its normal position shown in Fig. 11, the spring pressure of switch unit 22 exerted against projection 21 of armature arm 19, and the pressure of helical spring 46 against projections 47 and 48 of lever 41 being the means for such restoration. Switch unit 22 correspondingly returns to its normal position shown in Fig. 3, and lever 41 to its normal position shown in Fig. 11. Lever 42, however, remains latched by lever 43. As lever 41 restores to the left, projection 65 of lever 41 is withdrawn from projection 52 of lever 44, and the stored up energy in flat spring 51 causes lever 44 to quickly move to its top position since the lower arm of lever 42 is maintained away from stop stud 53 of lever 44 by the latching of lever 42 (Figs. 10 and 11). Projection 62 of lever 44 accordingly raises bushing 64 thereby operating switch unit 25 to the position shown in Fig. 11. The upward movement of lever 44 also raises lever 43, causing the tip end of the upper arm of lever 43 to pivot in notch 56 of lever 42, helical spring 58 serving to maintain the right-hand tip end of lever 43 in notch 56 of lever 42 (Fig. 11). The raising and pivoting of lever 43 causes the lower arm of lever 43 to come into contact with projection 67 of lever 41. In the manner described in this paragraph, switch unit 25 is operated responsive to winding 11 being de-energized after the first energization, and switch unit 25 remains in the operated position for the time being.

Assuming now that winding 11 is energized a second time, then armature 13 is again attracted towards core 10, and projection 21 of armature arm 19 (Fig. 3) correspondingly raises bushing 63 thereby again operating switch unit 22. As armature 13 moves from its normal position in Fig. 11 to the operated position of Fig. 12, pushing member 45 of armature arm 23 again moves lever 41 to the right. In this instance, however,

projection 65 of lever 41 moves sufficiently underneath projection 52 of lever 44 (Fig. 12) to lock lever 44 in its uppermost position, and switch unit 25, therefore, is locked in the operated position. Projection 67 of lever 41 presses against the lower arm of lever 43 thereby urging the tip of the upper arm of lever 43 out of notch 56, and lever 43, consequently, assumes the position shown in Fig. 12. Projection 55 of lever 41 pressing against shoulder 54 of lever 42, and stud 53 locked against the tip of the left-hand arm of lever 42, co-operate to retain lever 42 in the position shown in Fig. 12.

When winding 11 is de-energized for the second time, armature 13 is released and returns to its normal position in the manner previously explained for the first de-energization of winding 11. Switch unit 22 correspondingly returns to its normal position shown in Fig. 3, and lever 41 to its normal position shown in Fig. 9. As lever 41 restores to the left, projections 65, 55 and 67 of lever 41 also move to the left. Projection 65 clears projection 52 of lever 44 thereby unlocking lever 44: shoulder 54 of lever 42 follows projection 55 of lever 41, and the tip end of the left-hand arm of lever 42 correspondingly bears down on stop stud 53 of lever 44; and the spring pressure of switch unit 25 exerted against projection 62 of lever 44 assists lever 42 to quickly restore lever 44 to its lowest position, and switch unit 25 restores to its normal position shown in Fig. 9. The movement of the right-hand arm of lever 42 to the left also causes its tip end to pass underneath the tip end of the upper arm of lever 43 (Fig. 9) while projection 67 of lever 41 still maintains lever 43 in the position shown in Fig. 12, and these two tip ends accordingly assume the relationship shown in Fig. 9. One complete operation of the relay has now been accomplished.

Pushing member 45 is tapped into armature arm 23 and fitted with a slotted head and lock nut 66 in order that the movements of lever 41 can be suitably regulated to accomplish the described sequential operations of levers 42, 43 and 44.

From the foregoing description and the accompanying drawings it is readily apparent that a new, novel and useful relay structure has been devised. Recapitulating, one switch unit 22 of the relay is operated each time the relay is energized and is always restored each time the relay is deenergized; and the other switch unit 25 of the relay is operated only upon the first de-energization of the relay, remaining operated until and through the second energization of the relay, and is restored only upon the second de-energization of the relay. It is obvious that the described complete operation of the relay can be repeated as often as desired, either from time to time or continuously for any required number of times.

It should be understood that while one embodiment of the invention is disclosed and described in this specification the invention is not limited to the particular form or application shown, but is entitled to the equivalents thereof within the scope of the appended claims.

I claim:

1. In a relay, an electromagnet, an armature, a switch, means for energizing and de-energizing said magnet, means for causing different movements of said switch, a spring, said armature operated responsive to an energization of said magnet, locking means controlled by said operation of said armature for locking said switch

movement means to prevent a movement of said switch at this time, means controlled by said operation of said armature for conditioning said spring preparatory to causing a movement of said switch movement means, said operated armature fully restored responsive to a deenergization of said magnet following said one energization of said magnet, said locking means controlled by said restoration of said armature for unlocking said switch movement means, said conditioned spring responsive to said unlocking of said switch movement means for moving said unlocked switch movement means to cause one movement of said switch, said restored armature re-operated responsive to a re-energization of said magnet, said locking means controlled by said re-operation of said armature for locking said moved switch movement means to maintain said moved switch in its moved position, means controlled by said re-operation of said armature for differently conditioning said spring preparatory to causing a different movement of said locked moved switch movement means, said re-operated armature restored responsive to a second de-energization of said magnet, said locking means controlled by said last restoration of said armature for unlocking said moved switch movement means, and means including said differently conditioned spring responsive to said unlocking of said moved switch movement means for differently moving said unlocked moved switch movement means to cause a different movement of said moved switch.

2. In an electromagnetic relay, an armature, means for operating and restoring said armature, a movable bar, a lever having two arms rockable about a fixed pivot, a tensioned power spring having two ends, one end of said spring fixed to one arm of said lever, the other end of said spring engaging said bar under tension preparatory to causing a movement of said bar in one direction, said other arm of said lever oppositely engaging said bar under tension of said spring for preventing a movement of said bar in said one direction, locking means controlled by an operation of said armature for engaging said bar to lock said bar against a movement in said one direction, means controlled by said operation of said armature for rocking said lever to disengage said other arm of said lever from said bar and to move said one arm of said lever thereby to increase the tension in said other end of said spring, means responsive to said rocking of said lever for locking said rocked lever to maintain said increased tension in said other end of said spring, said locking means controlled by a restoration of said armature following said operation of said armature for moving said locking means to its unlocked position to free said bar for movement in said one direction, said additionally tensioned other end of said spring responsive to said last mentioned movement of said locking means for causing a movement of said unlocked bar in said one direction.

3. In an electromagnetic relay as claimed in claim 2 wherein said locking means is further controlled by a reoperation of said armature for differently engaging said moved bar to prevent a movement of said moved bar in a different direction, together with means controlled by said re-operation of said armature for unlocking said locked rocked lever, means including said one end of said spring responsive to said unlocking of said rocked lever for oppositely rocking said unlocked lever to cause said other arm of said

5 oppositely rocked lever to re-engage said locked moved bar preparatory to causing a movement of said locked moved bar in said different direction, said differently engaged locking means controlled by a second restoration of said armature for freeing said moved bar for movement in said different direction, and means including said re-engaged other arm of said differently rocked lever responsive to said last mentioned controlment of said differently engaged locking means for causing a movement of said unlocked moved bar in said different direction.

4. The electromagnetic relay claimed in claim 3 together with an electrical contact, means controlled by said moving of said bar in said one direction causing said contact to operate, said last mentioned means controlled by said moving of said bar in said different direction for causing said operated contact to restore.

5. The electromagnetic relay claimed in claim 2 together with an electrical contact, and means controlled by said moving of said bar in said one direction for causing said contact to operate.

6. In a relay, an electromagnet, means for energizing and de-energizing said magnet, an armature, a contact, a movable bar, a tensioned spring engaging said bar preparatory to causing a movement of said bar, a first locking means controlled by said spring for locking said bar against movement by said spring, said armature operated responsive to an energization of said magnet, a second locking means moved by said operation of said armature for additionally locking said bar against movement by said spring, means controlled by said movement of said second locking means for actuating said first locking means to partially unlock said bar for movement and to additionally tension said spring, means controlled by said actuation of said first locking means for holding said first locking means in its actuated position to maintain said additional tensioning of said spring, said operated armature fully restored responsive to a de-energization of said magnet, said second locking means controlled by said restoration of said armature for completely unlocking said partially unlocked bar, said additionally tensioned spring responsive to said complete unlocking of said bar for causing a movement of said bar, and means controlled by said movement of said bar for operating said contact.

7. In a relay, means for energizing and de-energizing said relay, an armature, an electrical contact, a movable element, a first locking means, means for causing said first locking means to lock said one element against movement, a first energization of said relay causing said armature to operate, a second locking means actuated responsive to said operation of said armature for additionally locking said one element, means controlled by said actuation of said second locking means for moving said first locking means to partially unlock said one element, means controlled by said movement of said first locking means for conditioning said locked element preparatory to causing an operation of said contact, a first de-energization of said relay causing said operated armature to restore fully, said actuated second locking means controlled by said restoration of said armature for completely unlocking said conditioned element, means responsive to said complete unlocking of said conditioned element for moving said conditioned element, an eighth means controlled by said movement of said one element for operating said con-

tact, a second energization of said relay causing said restored armature to re-operate, said second locking means re-actuated responsive to said re-operation of said armature for locking said one element in its moved position to retain said contact operated, means controlled by said re-actuation of said second locking means for differently conditioning said locked moved element preparatory to causing a restoration of said operated contact, a second de-energization of said relay causing said re-operated armature to restore fully, said re-actuated second locking means controlled by said last restoration of said armature for unlocking said differently conditioned element, means including said first locking means responsive to said unlocking of said differently conditioned element for restoring said differently conditioned element to its normal position, said eighth means responsive to said restoration of

said one element for causing said operated contact to restore.
